4 Claims. (Cl. 292—127)

ABSTRACT OF THE DISCLOSURE

This invention relates to a latch for securing a cover to an enclosure. It consists of a spring projected pivoted hook mounted on the cover and adapted to engage a keeper on the enclosure. The hook is both held in disengaged position and cammed to disengaged position by a finger operated plunger member.

The present invention relates to a latch for containers such as luggage, jewelry cases or the like. More particularly, it relates to a latch in which the movement of a single pushbar actuates the latch so that the container on which it is mounted can be readily opened.

Latches designed for use on containers such as jewelry cases and luggage should combine the features of pleasing appearance and compact design with ease of operation and simple construction.

A pleasing and quality appearance is important since the quality of containers such as luggage is often measured by the quality of their hardware. Because these containers are relatively small, compact design of hardware becomes more important. Such a compactly designed latch may be attached in a limited area on the container and encased in a housing which blends with the container design.

Because of its small size such a latch requires ease of operation, and manipulation with one hand is important since the usual mounting is in pairs. Quick and positive engagement and disengagement of the latch is highly desirable to eliminate fumbling with small parts; spring biasing aids in this regard. In addition, spring biasing minimizes slippage between parts and provides a solid "feel," so important in quality in luggage hardware.

Latches used on small containers constitute an appreciable factor in total container cost. The latch should, therefore, be simple in design and require no more than a minimal number of readily formed parts. However, quality appearance and ease of operation must be maintained even though the construction is simplified.

Accordingly, a principal object of the present invention is to provide a cam actuated latch of simple construction and compact design.

Another object of the present invention is to provide a latch of the above character which is easily installed, efficient in operation and pleasing in appearance.

Yet another object of the present invention is to provide a latch of the above character which can be manufactured inexpensively with a minimum amount of labor.

A further object of the present invention is to provide a latch of the above character which lends itself to use on small containers.

Other objects of the invention will in part be obvious and in part appear hereinafter.

The invention accordingly comprises the features of construction, combinations of elements, and arrangement of parts which will be exemplified in the constructions hereinafter set forth, and the scope of the invention will be indicated in the claims.

For a fuller understanding of the nature and objects of the invention, reference should be had to the follow-

2

ing detailed description, taken in connection with the accompanying drawings, in which:

FIGURE 1 is a perspective view of the present latch in open position, mounted on a hinged container.

FIGURE 2 is a lateral sectional view of the latch plate assembly taken along the line 2—2 in FIGURE 1.

FIGURE 3 is an exploded perspective view showing in disassembly the various parts of the hook assembly of the cam actuated latch of the present invention.

FIGURE 4 is an exploded perspective view showing in disassembly the various parts of the plate assembly of the latch of this invention.

FIGURE 5 is an elevated section of the interior of the latch construction when in the closed position.

FIGURE 6 is an elevated section of the interior of the latch construction when in the disengaged position.

Similar reference characters refer to similar parts throughout the several views of the drawings.

In general, and with reference to FIGURE 1, the latch of the present invention is designed to be used as a closure for a hinged container such as luggage, or the like. A hook assembly 8 containing a hook 10 and an alignment stud 12 is attached to the hinged cover 14 of a container 15. A plate assembly 16 containing a catch 18, an alignment slot 20 and a pushbar 22, is attached to the container base 24. When cover 14 is closed, alignment stud 12 enters alignment slot 20 and guides hook 10 into engagement with catch 18 securing cover 14 in a shut position. Hook 10 can be disengaged from catch 18, as described hereinafter, by pushing upwardly on pushbar 22. Once hook 10 has been disengaged, cover 14 can be easily opened.

Referring now to FIGURE 3, hook assembly 8 of the present latch is shown in disassembly. It comprises a backing plate 26 having two tabs 28 extending rearwardly thereof which are used to attach the hook assembly to a container top 14 (FIGURE 1). An integral flange 30 extends the length of backing plate 26 and two spacers 32 project forwardly from its sides. An integral alignment stud 12 projects downwardly from backing plate 26 adjacent one end thereof. An upstanding circular rim 34 is formed on the front of backing plate 26 about hole 36, to act as an axle for the hook 10.

As is most clearly seen in FIGURES 3 and 5, hook 10 is pivotally supported on circular rim 34 with its upper edge projecting through a clearance slot 38 in flange 30 and with a surface 44 adjacent a stop 40 at the bottom of plate 26. A lug portion 46 of hook 10 projects downwardly, and an extension 48 of the hook has a cam surface 50 and a wedging surface 52 adjacent but spaced from lug portion 46. A spring retaining flange 54 is positioned immediately above extension 48.

Backing plate 26 with hook 10 pivotally mounted interferes with a hook housing 56 (FIGURES 3 and 5), flange 30 and spacers 32 abutting the rear surface 58 of housing 56. A V-shaped spring 60 is compressed and mounted in hook housing 56 (FIGURE 5) with its upper arm 62 engaging flange 30 on backing plate 26 and its lower arm 64 biasing on flange 54 of hook member 10. Tabs 65a, 65b and 65c (FIGURE 3) are bent over backing plate 26 to complete the assemblage 8. This hook assembly 8 can then be mounted on cover 14 of a hinged container 15 (FIGURE 1).

The plate assembly 16 (shown in FIGURE 4) comprises a housing 66 having an alignment slot 20 formed in its top surface 70. An aperture 68 in top 70 adjacent alignment slot 20 has an edge 71 forming a portion of catch 18 by engaging lug 46 (FIGURE 3) on hook 10 (FIGURE 5) when in closed position. A keyhole 72 is formed in the face 74 of plate housing 66 and bottom flanges 76 extend rearwardly therefrom (FIGURE 4).

As seen in FIGURE 4, a pushbar guide 78 fits in plate housing 66 (FIGURE 2) having a keyhole 80 in alignment with plate housing keyhole 72; upper and lower flanges 82 fit under top 70 and the flanges 76 of housing 66. Edge 84 of one of the flanges 82 acts with edge 71 of housing 66 to form catch 18, as seen in FIGURES 5 and 6. Two guide rails 86a and 86b extend rearwardly from the ends of pushbar guide 78, each terminating in a tab 88; these may be used to secure assembly 16 to the container in alignment with hook assembly 8 as shown in FIGURE 2.

Pushbar 22 (FIGURES 1 and 4) between guide rails 86a and 86b (FIGURES 2 and 5) is mounted for vertical sliding. A cam actuator projection 90 protrudes from the upper edge of pushbar 22 and its upper surface 92 is rounded for sliding contact with camming surface 50 of hook member 10 as seen in FIGURE 5. A locking dowl 94 extends perpendicularly from the back surface of pushbar 22.

A tumbler 96 (FIGURES 4 and 5) is mounted in plate assembly 16 behind pushbar 22 with an edge 98 thereof in contact with guide rail 86a (FIGURE 5). Tumbler 96 and locking dowl 94 form part of a lock mechanism to be described.

A backing member 100 (FIGURE 4) contains two vertical slots 102 spaced to accommodate tabs 88 on pushbar guide 78. A flange 104 projects from the front surface of backing member 100 to support the bottom edge 106 of tumbler 96 when the parts are assembled in the plate assembly (FIGURES 5 and 6). Two spacing tabs 108 extend from the front surface of backing member 100 to abut the face 74 of plate housing 66. These tabs 108 provide clearance in the plate assembly 16 so that pushbar 22 and tumbler 96 can slide in their respective directions. A detent 110 protrudes from the front surface of backing member 100 and forms still another portion of the lock mechanism. Backing member 100 contains the component parts of plate assembly 16 with tabs 112 on plate housing 66 extending thereover as shown in FIGURE 2.

Operation of latch

Referring to FIGURE 1, when cover 14 of container 15 is closed alignment stud 12 enters alignment slot 20 and aligns hook assembly 8 with plate assembly 16. The positioning function of alignment stud 12 is most important, particularly where container 15 is slightly warped or overfilled and cover 14 and base 24 are out of alignment. As alignment stud 12 moves into alignment slot 20, the edge 46a of lug 46 contacts the edge 71 of catch 18 causing hook 10 to pivot clockwise about axle 34 to compress spring 60 finally to the position shown in FIGURE 6. As tip 46b (FIGURE 5) of lug 46 clears edge 84 of catch 18, spring 60 urges hook 10 in a counter-clockwise direction whereby lug 46 securely engages catch 18 as shown in FIGURE 5. Container 15 is thereby held firmly in a closed position.

To open the latch, pushbar 22 is pressed upwardly (FIGURES 5 and 6). Rounded surface 92 of cam actuator 90 contacts camming surface 50 causing hook 10 to pivot clockwise. Spring 60 is thus caused to compress, while lug 46 is disengaged from catch 18. As tip 48a of cam 48 rotates past tip 90a of cam actuator 90 (FIGURE 5), cam actuator 90 snaps into contact with wedging surface 52 of hook 10 as shown in FIGURE 6. Spring 60 wedges the pushbar 22 between wedging surface 52 and guide rail 86a. The lug 46 is thereby held disengaged from catch 18 and container top 14 is readily opened. Accidental re-engagement of the latch cannot occur with the latch in this disengaged position.

Upon opening the container, wedging surface 52 of cam 48 slides past cam actuator 90 in the direction of the arrow in FIGURE 6. When tip 48a of cam 48 clears tip 90a of cam actuator 90, the wedging force is released and pushbar 22 slides downwardly in pushbar guides 86a

and 86b. Hook 10 quickly rotates counterclockwise about axle 34 due to the biasing action of spring 60 until it contacts stop 40. The latch at this point is shown most clearly in FIGURE 1, in its open position.

Operation of lock mechanism

As shown most clearly in FIGURE 5, tumbler 96 is supported between flange 104 on backing member 100 and upper flanges 82 on pushbar guides 78, and can slide from side to side as indicated by the arrows in FIGURE 10 4. As best seen in FIGURE 2, protruding detent 110 on backing member 100 engages the arm 113 of tumbler 96 and prevents tumbler 96 from sliding from side to side in normal use of the latch. The latch, as shown in 15 FIGURE 5, is in an unlocked position.

To lock the mechanism, a key is inserted through key-holes 72 and 80 (FIGURE 2) in plate housing 66 and pushbar guide 78 respectively, and into key aperture 114 (FIGURE 4) in tumbler 96 where the key may bear 20 against either shoulder 116 or shoulder 118. The end of the key pivots in a hole 120 in backing member 100. As best seen in FIGURE 5, turning the key in a counter-clockwise direction will cause it to bear against shoulder 116 causing tumbler 96 to slide to the left. Tumbler 25 96 slides over detent 110, which is slightly depressed thereby, until detent 110 snaps into locking engagement with detent hole 122. Simultaneously, ledge 124 of tumbler 96 moves locking dowl 94 on pushbar 22. Thus, pushbar 22 is locked against upward movement and cam actuator 30 90 cannot contact with cam 48 to disengage hook 10 from catch 18. In the position described, the latch is locked.

Turning the key in a clockwise direction (FIGURE 5) will cause it to bear against shoulder 118 thereby moving tumbler 96 to the right. This removes ledge 124 from 35 the path of locking dowl 94 leaving pushbar 22 free to slide and placing the latch in an unlocked position as shown in FIGURE 5.

Numerous advantages are obtained with the present 40 latch construction. The design is simple and compact and readily lends itself to attachment to small containers. In addition, the parts can be readily and inexpensively formed by stamping.

The latch is easy to operate, only one hand being 45 required to actuate the single pushbar 22. Further, the wedging action between pushbar 22 and hook 10 eliminates the chance of accidental re-engagement of the latch before the container top is opened. Thus, inconvenience to the operator is minimized. Also, the latch mechanism is spring biased providing for rapid and positive 50 engagement and disengagement while minimizing slippage between component parts.

It will thus be seen that the objects set forth above, among those made apparent from the preceding description, are efficiently attained and, since certain changes may 55 be made in the above constructions without departing from the scope of the invention, it is intended that all matter contained in the above description or shown in the accompanying drawings shall be interpreted as illustrative and not in a limiting sense.

It is also to be understood that the following claims are 60 intended to cover all of the generic and specific features of the invention herein described, and all statements of the scope of the invention, which, as a matter of language, fall therebetween.

Having described our invention, what we claim as new 65 and desire to secure by Letters Patent is:

1. A latch for securing the cover and base of a hinged container comprising, in combination:

(A) a hook assembly adapted for attachment to said 70 cover, said hook assembly comprising
(1) a hook pivotally mounted in said hook assembly and having
(a) means thereon for engaging a catch to secure said container when said cover is closed,

- (b) a camming surface
    - (i) integral therewith, and
    - (ii) oriented so that pressure exerted thereon will cause said hook to pivot out of engagement with said catch;
  - (B) a plate assembly adapted for attachment to said base, said plate assembly comprising
    - (1) a catch
      - (a) aligned to engage said hook when said cover is closed,
    - (2) a pushbar
      - (a) mounted in said plate assembly, and
      - (b) slidable along a path in said plate assembly in a direction substantially normal to the axis of said hook,
      - (c) said pushbar having an actuator projecting therefrom which is in alignment with said camming surface when said cover is closed, and
      - (d) holding means on said actuator engageable with said hook for releasably maintaining said hook disengaged from said catch until said latch is opened,
- whereby movement of said pushbar toward said hook causes said actuator to slidably bear against and exert pressure on said camming surface to pivot said hook out of engagement with said catch.
2. A latch as defined in claim 1 further comprising

integrated locking means movable between locked and unlocked positions, said locked position serving to block the movement of said actuating means thereby preventing the disengagement of said hook from said catch when said cover is closed.

5 3. A latch as defined in claim 1 having a spring compressively mounted in said hook assembly in contact with said hook whereby said hook is biased about said axle in a direction opposite to the direction of the pressure exerted by said actuating means when moved against said camming surface.

10 4. A latch as defined in claim 1 having a stud protruding from one said assembly and means forming an aperture in the other said assembly for receiving said stud whereby said hook assembly is aligned with said plate assembly when said cover is closed.
